PICKER SPINDLE FOR LOOMS

Carl J. Lindegren, Providence, R. I., assignor to Crompton & Knowles Loom Works, Worcester, Mass., a corporation of Massachusetts

Application February 11, 1932, Serial No. 592,339

4 Claims. (Cl. 139—158)

This invention relates to picker spindles and it is the general object of the invention to provide a spindle which is self-lubricated so as to render unnecessary the application of oil directly to the spindle.

Box looms and the plain end of certain weft replenishing looms are provided with picker spindles along which the shuttle propelling picker moves. These spindles become heated unless properly lubricated, but because of the danger of spattering oil on the yarn and fabric, the spindle is oiled very sparingly. As a consequence, sufficient heat sometimes develops to bend the picker spindle in its mounting the result of which is to curve the spindle so that it throws the shuttle out of the loom. It is an important object of my present invention to prevent this heating by providing a spindle having a groove in which is located a substance capable of absorbing oil, this substance preferably being held together by a metallic core.

It is another object of my invention to provide one end of a spindle with an oil chamber which communicates with the aforesaid slot, the wire of the absorbent material together with the latter passing from the groove into said chamber and being compressed therein so as to form an anchor the effect of which is to hold the absorbent material firmly in position. The outer end of the chamber may be closed by any suitable valve, such as that found on various lubricating systems, and the hole connecting the groove with the chamber sufficiently large to permit a sufficient feeding of oil to keep the spindle properly lubricated.

It is a further object of my invention to provide the spindle with an internal reservoir of oil which communicates with a longitudinal groove on the periphery of the spindle at a point along the spindle which is between the ends of the picker when the latter is in normal non-picking position. In this way assurance is given that as soon as the oil arrives in the groove it will be in position to lubricate the picker bore. The picker will ordinarily move along the spindle in the direction away from the point of communication between the groove and reservoir. By this arrangement the interior of the picker bore is in most favorable position to be lubricated during periods of inaction on the part of the loom. In assembling the various parts of the spindle I preferably insert a length of the wick into the oil chamber and pick the same so as to form an effective anchor, after which the wick is stretched along the groove and then clamped by means of

a plug or the like which binds the metallic core of the wick tightly in position and serves to take up any slack which might exist in the wick.

With these and other objects in view which will appear as the description proceeds, my invention resides in the combination and arrangement of parts hereinafter described and set forth in the claims.

In the accompanying drawing, wherein a convenient embodiment of my invention is set forth,

Fig. 1 is a rear elevation of one end of a loom lay having my invention applied thereto,

Fig. 2 is a top plan view of the structure shown in Fig. 1,

Fig. 3 is an enlarged rear elevation of the spindle,

Fig. 4 is a top plan view of the structure shown in Fig. 3,

Fig. 5 is a vertical section taken on line 5—5 of Fig. 4, and

Fig. 6 is a vertical transverse section on line 6—6 of Fig. 5.

Referring particularly to Figs. 1 and 2, I have shown a lay 10 having a lay end 11. The latter is provided with ears 12 between which lies the eye end 13 of a spindle S. A pin 14 passing through the ears and eye affords a pivotal support between the spindle and lay. The outer end of the lay is provided with a support 15 held by screws 16 and perforated to receive the outer end of the spindle.

The shuttle boxes 17 are mounted for reciprocation with respect to the lay in the usual manner so as to present one or another of a plurality of shuttles to active position. A picker 19 actuated by the picker stick 20 is movable along the spindle.

The matter thus far described may be as set forth in my prior Patent No. 1,807,743.

My present invention relates more particularly to the spindle proper, and by referring to Figs. 3, 4 and 5 it will be seen that the shank or body of the spindle is provided at its upper side with a groove 30 which extends throughout the greater part of the length of the spindle, although it need not extend to either end, and as shown herein terminates short of the outer end of the spindle. As shown in Fig. 5 the outer end of the spindle is bored so as to afford an oil chamber 31 which may be closed by an appropriate fitting 32 having a common form of ball lock or valve 33 held in oil retaining position by spring 34. The fitting is shown herein as screwed into position to prevent oil leakage, but it may be secured to the spindle in any other way which will effec-

tively prevent loss of oil. A connecting passage 35 is provided between the chamber 31 and groove 30 and is the means by which oil can be transmitted from the chamber to the groove.

There is located in the groove a wick element 40 which may have a wire core formed of two or more flexible wires twisted together and gripping tufts of textile material, such as felt, wool or cotton or any other material having capillary properties rendering it capable of absorbing and transmitting oil. The wick has the left hand end thereof as viewed in Fig. 2 held in position by means of a plug 41 driven into the spindle. The wick lies within the groove, with the tufts thereof projecting slightly above the cylindrical surface of the spindle to lie in the path of the picker.

The wick is projected through the connecting passage 35 and a sufficient amount of it is deformed as at 50 to form an anchor to prevent loosening of the wick in the groove. It is to be understood that with frequent reciprocating movements of the picker along the spindle it is desirable to hold the wick in position and it is for this reason that I pack a length of the wick into the inner end of the oil chamber, the wire core of the wick serving to hold the packed mass in position.

In operation, the spindle will be applied to the loom so that the wick will be facing upwardly and by appropriate means a quantity of oil will be pushed around the ball lock into the oil chamber. That part of the wick which has been packed into the chamber will become saturated and the oil will travel along the wick through the passage 35 and along that part of the wick in the groove. As the picker moves back and forth it will therefore have its bore lubricated by small and unobjectionable amounts of oil which are gathered from the tufts of the wick.

It will be seen from the foregoing that I have provided a simple form of self-oiling picker spindle having a small supply of oil located at one end to saturate a wick which extends along the groove in the spindle. The wick may have a metallic core such as will permit picking of a part of the same into the end of the chamber to form an anchor, in this way resisting outward movement of the wick through the passage 35. It will be seen by re-

ferring to Fig. 2 that the picker when in normal non-active position surrounds that part of the spindle through which the passage 35 is located, and when the oil is first raised by capillary attraction through this passage it reaches a position where it can lubricate the picker when the latter is at rest. This result is achieved by having the outlet which connects the oil chamber with the groove located next the outer end of the spindle and between the ends of the bore in the picker when the latter is at rest. It will also be seen that I have produced an improved form of wick having a metallic core which serves to hold the wick in the groove and is not subject to stretching. For this reason the wick is found in practice to lie within the groove and not be disturbed by movements of the picker. Also, the eye end of the spindle serves to hold the wick on the upper side of the spindle.

Having thus described my invention it will be seen that changes and modifications may be made therein by those skilled in the art without departing from the spirit and scope of the invention and I do not wish to be limited to the details herein disclosed, but what I claim is:

1. In a loom picker spindle having a longitudinal groove, a lubricant reservoir connecting with the groove, and a wire cored wick lying in the groove and extending into the reservoir, a portion of the wick being packed into the reservoir to act as an anchor to hold the wick.

2. A picker spindle comprising a rod having a lubricant reservoir located therein and a wire cored wick extending from the reservoir along the rod, a part of the wick being deformed and located in the reservoir to act as an anchor to hold the wick to the rod.

3. A picker spindle comprising a rod having a lubricant reservoir located therein and a wire cored wick extending from the reservoir along the rod, a part of the wick being deformed and located within the rod to act as an anchor to hold the wick to the rod.

4. A picker spindle comprising a rod having a lubricant reservoir, and a wick having a core of wire and a lubricant conveying substance in communication with the reservoir, the wire core being bent back on itself to form an anchor having holding relation with the rod.

CARL J. LINDEGREN.
